CONTROL

Charles D. Geer and John L. Blach, New Haven,
Conn., assignors to The Engineering and Re-
search Corporation, New Haven, Conn., a cor-
poration of Connecticut

Application April 8, 1930, Serial No. 442,560

3 Claims. (Cl. 177—329)

This invention relates to a control having functionally and structurally improved characteristics.

Subject matter specific to the structure shown in Figure 2, is claimed in application S. N. 69,622 filed March 19, 1936, as a division of the present application. Subject matter specific to the structure of Figure 1 is claimed in application S. N. 69,623 filed March 19, 1936 which is also a division 10 of the present application.

It is an object of the invention to construct a mechanism of this character which will be capable of advantageous use in numerous different associations but which has been primarily developed to provide a vehicle actuated control and when utilized in this connection being of major value when associated with a traffic control system.

A further object of the invention is that of providing a mechanism operable by a control and whereby a predetermined functioning of this mechanism is achieved only in the case of the control being operated in a predetermined manner. Accordingly, by means of the present invention, any difficulties which might be experienced incident to a functioning of the mechanism regardless of the operation of the control are avoided.

A still further object is that of providing structures of this character capable in certain respects of independent use but primarily adapted for cooperative functioning and which structures will involve relatively few parts individually simple and rugged in construction and capable of ready 35 assemblage and set-up to furnish mechanisms operating over long periods of time with freedom from electrical and mechanical difficulties.

With these and further objects in mind, reference is had to the attached sheet of drawings illustrating practical embodiments of the invention, and in which:

Fig. 1 is a diagrammatic illustration of a vehicle actuated control;

Fig. 2 is a similar view of the control in association with the mechanism to be operated thereby; and

Fig. 3 shows a slightly different layout of the system from that illustrated in Fig. 2.

Referring to Figs. 1 and 2 of the drawing there is shown a schematic embodiment of an impulse relay mechanism constructed in accordance with our invention and connected to a mechanism to be controlled. For the purpose of illustrating a practical embodiment of the invention, a mechanism to be controlled is indicated by the letter

"S" and may be for example a timer or an automatic traffic counter constructed and arranged to count vehicles moving along a highway.

The road unit 1 conveniently includes a body located in the street so as to be actuated by a vehicle passing over the device and causing contacts to be made in a predetermined manner. One novel feature of the invention is that these contacts may be connected to be effective to control the circuits only when the vehicle moves over the unit in a certain direction.

In the illustrated embodiment of our invention this unit includes three separate contact members 2, 3 and 4 insulated from each other by spacer members 5. These contact members are preferably yieldable plates which may readily be flexed into contact with each other as the vehicle passes over the device. The entire assemblage is located within a resilient moisture and waterproof envelope or casing indicated by the numeral 6. The contact plates 2, 3 and 4 are connected in circuit to a suitable source of electrical energy by means of lead wires 7, 8 and 9 respectively.

Connected in circuit with the switch members are electro-magnets 10 and 11 provided with armatures 12 and 13 respectively for opening and closing circuits as hereinafter described. Disposed adjacent the armature 12 are double contacts 14 and 15, a single contact 16 being provided adjacent the armature 13. Magnet 10 and armature 13 are connected in circuit with plate 2 by means of leads 8 and 17, and magnet 11 is connected in circuit with plate 3 and armature 12 by means of leads 9 and 20. The designated unit "S" to be controlled by the operation of the several switch members may, as shown in Fig. 2, be connected in circuit therewith by means of lead wires 18 and 19.

Having thus described one embodiment of a relay mechanism constructed in accordance with our invention, the operation thereof is as follows: Assuming that the switch mechanism 1 is located in a street pavement wherein it is desired to record the presence of vehicles passing only in the direction indicated by the arrow, the circuits for operating the counter or timer will be completed in the following manner. A passing vehicle wheel engages plate 2 and deflects it as indicated by the dotted line, Fig. 2, so as to contact with plate 4 thereby energizing relay 10 and causing armature 12 to engage contact 15 and supply current to unit "S" by lead wire 19. When the vehicle proceeds further over the unit, the gap is closed between plates 2 and 3 by the engagement of the latter with plate 4, and power is supplied 55

to "S" via plate 3, and leads 9 and 18; thus causing it to operate and register the impulse created by the passing vehicle. As the vehicle continues along the unit, contact between plates 2 and 4 is broken and magnet 10 is deenergized, thereby causing armature 12 to interrupt the circuit 19, and the mechanism is again at its normal condition of rest.

From the foregoing, it will be noted that the 10 impulse for operating the unit S is effected by the predetermined order in which contact is made between the plates 2, 4 and 3. To further illustrate the operation of the device: If a vehicle should approach in a direction opposite to that 15 indicated by the arrow, plate 3 first makes contact with plate 4 and thereby energizes relay 11 which causes armature 13 to interrupt the circuit 17 to magnet 10. As the vehicle proceeds and causes plate 2 to also engage plate 4, the circuit 20 to magnet 10 remains unchanged and thereby prevents relay 10 from becoming energized and thus the circuit 19 to the counter cannot be completed so as to produce an operative impulse. After the vehicle has passed off the unit 1, the 25 circuit conditions return to normal without producing any effects on the mechanism "S".

From the above description, it will be noted that it is necessary that the relays 10 and 11 be successively energized in a predetermined order 30 so as to permit an electrical impulse to operate the counter mechanism. Thus, we have provided a simple and efficient mechanism which shall accurately register vehicles passing over the device in only one direction.

35 Referring to Fig. 3, it will be observed that the same layout has been illustrated as that shown in Fig. 2 with the exception that the unit S is not connected directly into the operating circuit. More particularly, it will be noted that the circuit breaker 22 controlling the flow of current 40 through leads 23 is coupled in this view to be closed when the armature 13 is attracted by the electro-magnet 10. This may be achieved by having the circuit breaker 22 within the sphere of 45 influence of the magnet 11 or as has been indicated in dotted lines coupling the member 22 to the armature 13. Additionally, in this view it will be observed that the armature 13 in addition to operating with contact 16 for the purpose of 50 closing the circuit through electro-magnet 10 engages a contact 24 when attracted and this contact is connected to the lead corresponding to lead 20 in Fig. 2. Obviously, the same operation as that heretofore described will follow in connection 55 with the construction presently considered. In other words, current will not flow through the leads 23 unless the control is actuated in a predetermined manner.

The value of the present construction will be 60 apparent when it is considered that by means of the same, a vehicle moving over a highway in a direction contrary to that in which control is to be exercised will not effect operation of the present mechanism. In other words, a vehicle which 65 for example is on the wrong side of the road or overlaps the center thereof and has passed the intersection will not cause an actuation of the control mechanism even although it may traverse the control unit. Accordingly, no operation 70 of the timer and/or counter connected to this unit will follow, but the passage of the vehicle in a proper direction will immediately result in such operation.

In this connection it will be understood that the 75 present control has been illustrated as a road

unit. According to the present invention, this is preferably the case. However, it will be appreciated that in certain aspects the control might be of another construction and conversely that the mechanism operated thereby might be of different type without effecting detrimentally the results to be obtained.

It will moreover be appreciated that numerous changes in construction and rearrangements of the parts might be resorted to without departing 10 from the spirit of the invention as defined by the claims.

Having described our invention, what we claim as new and desire to secure by Letters Patent, is:

1. A control system including power supply leads, a pair of circuit makers for sequential operation, a pair of relays, the first relay having one side of its coil connected to one power lead and having an operating circuit for the other side of its coil via a break contact on the second 20 relay and via the second circuit maker to the other power lead, and having a holding circuit from said other side of its coil via a make contact operated when its coil is energized and via the first circuit maker to said other power lead, 25 and the second relay having one side of its coil connected to said one power lead and having an operating circuit from the other side of its coil via a break contact on said first relay and via the first circuit maker to said other power lead, 30 and having a holding circuit from said other side of its coil via a make contact operated when its coil is energized and via said second circuit maker to said other power lead, and a register circuit operated by operation of one of said 35 relays.

2. A control system including power supply leads, a pair of circuit makers for sequential operation, a pair of relays, an operating circuit for a first of said relays extending from one 40 power lead thru a second of said circuit makers thru a break contact and armature of the second relay and thru the coil of said first relay to the other power lead, a second operating circuit for said second relay extending from said one 45 power lead thru said first circuit maker thru a break contact and armature of said first relay and thru the coil of said second relay to said other power lead, a holding circuit for said first 50 relay extending from said one power lead thru said first circuit maker thru a make contact and said armature of said first relay thru the coil of said first relay to the other power lead, a holding circuit for said second relay extending from said one power lead thru said second circuit maker thru a make contact and said armature of said second relay thru the coil of said second 55 relay to the other power lead, and a registering circuit operated solely by operation of said second relay.

3. A control system including a pair of circuit makers for sequential operation, a pair of relays, the first circuit maker being connected across power supply leads through a break contact and armature on a first relay and the coil of a second 65 relay, and the second circuit maker being connected across the power supply leads through a break contact and armature of the second relay and the coil of the first relay, a holding circuit for the first relay including a make contact on the first relay for connecting its coil via its armature in series with the first circuit maker across the power supply leads to be operated only by and during closure of the latter when the first 70 relay coil is energized, a holding circuit for the 75

second relay including a make contact on the second relay for connecting its coil via its armature in series with the second circuit maker across the power supply leads to be operated only by and during closure of the latter when the second relay coil is energized, a register circuit, and a contact on said second relay for operating said register circuit when said second relay is energized, whereby sequential operation of the

circuit makers in the order first, first and second, second causes operation of the register circuit only throughout the sequence, and sequential operation in the opposite order prevents operation of the register circuit only throughout the sequence.
